VERNON ROYLE, OF PATERSON, NEW JERSEY

STRAINER HEAD FOR TUBING MACHINES

Application filed August 11, 1927. Serial No. 212,298.

This invention relates to an improvement in strainer heads for tubing machines.

It has for an object to provide a device of this character that will adapt the machine for satisfactory and expeditious operation upon materials of varying characteristics without producing an undue strain upon any of the parts or irregularity of operation.

Another object is to provide a device of this character which will substantially increase the output of the machine in given periods of time and with given operating power.

Another object consists in providing a device of this character which includes means for controlling the temperature of the inner member of the strainer head.

A further object consists in providing certain improvements in the form, construction and arrangement of the several parts, whereby the above named and other objects may effectively be attained.

Machines of this kind are designed to operate upon rubber compounds, including various substances, during the process of reclaiming the rubber; and these compounds and substances differ greatly in character and consistency. Consequently the designing of a strainer head entails problems directly related to the effort to construct a device of this kind which will give a large output of adequately strained material for a given unit of time and with a given expenditure of power. My invention is calculated to enhance the capacity of the device in these respects, as well as embodying advantages inherent in the construction.

A practical embodiment of the invention is shown in the accompanying drawings in which

Fig. 1 represents a front elevation of the strainer head;

Fig. 2 represents a longitudinal section taken in the plane of the line II—II of Fig. 1 looking in the direction of the arrows;

Fig. 3 represents a section taken in the plane of the line III—III of Fig. 2 looking in the direction of the arrows;

Fig. 4 represents a section taken in the

plane of the line IV—IV of Fig. 2 looking in the direction of the arrows;

Fig. 5 represents an enlarged detail view, partly in elevation and partly in section, of the inner member of the strainer head;

Fig. 6 represents an enlarged detail longitudinal section taken in the plane of the line VI—VI of Fig. 4 looking in the direction of the arrows; and

Fig. 7 represents a similar view taken in the plane of the line VII—VII of Fig. 4 looking in the direction of the arrows.

The head of the tubing machine may be of any well known or approved form. Its front portion only is shown, and is represented in the drawings by 1. The usual screw or plodder 2 is housed within the liner 3 of the tubing machine head, in the usual way, and projects therefrom for cooperation with the strainer head.

A set of four stud bolts 4 stand out from the tubing machine head 1, and are intended to register with holes formed in the face plate 5 of the strainer head. Nuts 6 are provided for threading on to the bolts 4 in order to secure the face plate 5, and hence the strainer head, in position on the tubing machine.

The strainer head includes an inner member marked 7 that is shouldered at 8 to match a reduced flange 9 that projects forwardly from the bore liner 3. A suitable washer 10 may be placed between the machine head 1 and the bore liner 3 on the one hand, and the face plate 5 and inner member 7 on the other hand.

The inner member 7 is also shouldered, as shown at 11, for engagement with a corresponding shoulder formed in the face plate 5; and it will be noted that the shoulders 8 and 11 of the inner member 7 are oppositely faced. The inner member 7 is further provided with a threaded flange 12 that mates with a threaded flange 13 on the face plate 5.

As a result of the construction just described, it will be seen that the parts are assembled by screwing the inner member 7 into the face plate 5 until the shoulder 11 firmly abuts the face plate; after which the face plate and inner member carried thereby are

secured to the machine head by the bolts 4 and nuts 6.

The device also includes means for controlling the temperature of the inner member 7, as by the circulation therein of a heating or cooling medium. To this end the inner member has embedded therein a series of U-shaped tubes, one of which is denoted by 14; see Fig. 5. These tubes may be put in place by 10 routing or otherwise cutting out the surface of the inner member 7 and then covering over the tubes with strips of metal or other suitable material appropriately secured in place.

One end of each tube 14 opens into a radially disposed port 15, which said ports are flared at their outer ends and communicate with an annular channel 16 fashioned partly in the inner member 7 and partly in the face plate 5. The said annular channel 16 communicates with a plurality of ducts 17 that, in turn, communicate with a passage 18 circularly formed in the face plate 5, which passage is intended to be fed with temperature controlling medium such, for instance, as 20 steam or water through any suitable opening in the machine head 1 or face plate 5.

The other end of each tube 14 terminates short of the routed or otherwise cut groove formed in the inner member 7 for receiving 30 the tube. The said groove is plugged by a screw plug 19 so as to form between the said plug and the end of the tube 14 a little chamber 20 that is in communication with a duct 21 which opens into another passage 22 that 35 is formed partly in the inner member 7 and partly in the face plate 5. This passage 22 may be opened to air or to suitable exhaust piping, or the like, by means of any appropriate opening formed in the machine head 1 or the face plate 5.

As a result of this arrangement it will be evident that the temperature controlling medium may be injected into the passage 18 and, by virtue of the connections, pass through the 45 tube 14 and out through the passage 22. Of course, if desired, the flow could be reversed. Any practicable number of such tubes may be arranged in the inner member 7 of the strainer head and, in the present instance, I 50 have shown eight.

The inner member 7 has its cylindrical surface pierced by a number of longitudinally disposed rows of elongated perforations 23 for the passage of the material to be strained 55 as it is forced into the strainer head by the screw. These perforations are so arranged that a branch of some one of the temperature controlling tubes 14 lies in the wall of the inner member 7 between any given pair of 60 rows of perforations. Another way of expressing the same thought is to note that a branch of a temperature controlling tube lies on each side of any given row of perforations. This provides for a thorough and uniform 65 control of the temperature of the inner mem-

ber 7 throughout substantially its entire area.

The perforations 23 are preferably comparatively large and their size, as well as their elongated shape, enables rapid passage of the material from the inside to the outside 70 of the member 7, thereby increasing the output of the machine at this juncture. The elongated shape of the perforations 23 also enables the desired size of the perforations to be attained without making them so wide 75 in circumferential direction as to space the branches of the temperature controlling tubes 14 too far apart.

It will be seen, by reference to Figs. 3, 4, and 5, that the side walls of the perforations 80 23 lie in planes oblique to the radii of the inner member 7. This arrangement is of some importance because it enables the edges of the said perforations to cooperate with the screw by a sort of shearing action and thus 85 scrape the material from the screw. This angular disposition of the perforations also facilitates the escape of the material from within the member 7, because the material is to a certain extent rotated by the screw, and the oblique direction of the holes does not call for such a change in the movement of the material being forced from the member 7 as would be occasioned if the sides of the 90 said perforations were substantially parallel 95 to a radius. The direction of rotation of the screw is indicated by arrows on Figs. 3 and 4.

The outer member, or jacket, of the strainer head, is composed of two halves 24, 25. 100 Each of these is semi-cylindrical in form so that, when they are in abutment, a cylinder is formed which surrounds and is concentric with the inner cylindrical member 7.

The halves of the outer member 24, 25, 105 have hinge knuckles 26, 27, at their rear ends which are fitted to receive pintles 28, 29, mounted, as by cotters 30, 31, in lugs 32, 33, 34, 35, formed on the front of the face plate 5.

This mounting enables the members 24, 25, to be swung open or to be swung into substantial abutment with each other, which latter is their operative position.

In order firmly to hold the said halves 24, 25 in their closed position, I provide lock bars 115 36, 37, which have hinge knuckles 38, 39, at their rear ends, which embrace pintles 40, 41, fixed by cotters 42, 43, in lugs 44, 45, 46, 47, mounted above and below the halves 24, 25, on the front of the face plate 5. 120

The lock bars are longitudinally grooved, as indicated at 48, 49, for engagement with the adjacent edges of the halves 24, 25, and the side ribs on the lock bars, formed by the presence of the grooves 48, 49, are fitted to enter channels 50, 51, 52, 53, formed in the faces of the said halves 24, 25. It will be noted that the outer walls of the said grooves 50, 51, 52, 53, are flared so as to facilitate the entry of the complementary parts of the lock 130

bars therein, while the opposite walls of the said grooves are shaped so as tightly to fit within the grooves 48 and 49 in the lock bars.

The outer member or jacket of the strainer head composed of the parts 24, 25, has its cylindrical walls perforated with a multiplicity of holes 54, and it will be observed that these holes are substantially radially disposed, that they are considerably smaller than the perforations 23 in cross-sectional area, and that they are located more closely together than are the perforations 23.

A screen 55, cylindrical in form, is set between the inner and outer members of the strainer head, and preferably lies against the inner surface of the halves 24, 25, of the outer member. This provides adequate support for the screen, and the fact that the holes 54 in the outer member are comparatively small in cross-sectional area obviates the existence of any substantial unsupported surface of the screen which might be distorted by the force of the ejected material.

In order to support and prevent distortion of the adjacent edges of the halves 24, 25 of the outer member, I fasten upper and lower partitions 56, 57, to the upper and lower exterior walls of the inner member 7. Screws 58, 59, serve this purpose.

The front exterior portions of the halves 24, 25 composing the outer strainer head member, are threaded for receiving a correspondingly threaded ring nut 60.

The threads connecting these parts, which are marked 61, are slightly coned from the front toward the rear so as to increase the locking effect of the ring nut 60 which latter, as will be evident, serves firmly to hold the front ends of the halves 24, 25, in abutting engagement, thereby supplementing the action of the lock bars 36, 37. The function of the lock bars and ring nut is augmented by providing tapered noses 62, 63, on the lock bars which are fitted to enter correspondingly shaped recesses in the ring nut 60. This cooperative engagement is well shown in Fig. 2.

The strainer head also includes a front member which is marked 64, and is pierced throughout substantially its entire area by apertures 65. The cross-sectional area of these apertures is larger near their forward or outer portions so as to facilitate the escape of the material therethrough. A screen 66 is inserted between the front end of the inner member 7 and the front member 64.

This front member 64 is held in place by a ring 67 that is secured within the ring nut 60 by a radially disposed set of shear pins 68. The provision of these shear pins is desirable because experience has shown that, occasionally, the pressure within the strainer head will become so great as to tear the ring nut off the outer member or jacket, thereby damaging the parts. The strength

of the shear pins 68 is calculated so that they will give way before a pressure which would dislodge the ring nut 60 as approximated.

I preferably arrange the cooperative threaded portions of the jacket halves 24, 25, and ring nut 60 with longitudinal spaces between sections of thread, as indicated in dotted lines at 69, in Fig. 1. This provides a sort of breech-block lock engagement whereby the lock nut may first be forced axially substantially of its seated position on the halves 24, 25, and then, by a short movement in a rotary direction, be screwed home. This is a feature of some importance because the strainer head is a device which requires frequent disassembling for cleaning, and, occasionally, for repair or replacement of the screens.

As the ring nut 60, and ring 67 carried thereby, are sometimes of considerable weight, I have seated a band 70 in a peripheral groove formed in the ring nut 60 and fitted a bolt 71 in the upper ends of the band, which bolt may be engaged by the hook of suitable tackle for temporarily supporting the nut while it is being adjusted into position by the workman.

As the operation of the above described device will be obvious, from its description, to anyone skilled in the art, it is not deemed necessary to include a statement thereof.

It will be understood that various changes may be resorted to in the form, construction, and arrangement of the several parts, without departing from the spirit and scope of my invention; hence, I do not intend to be limited to the details herein shown and described except as they may be included in the claims.

What I claim is:

1. A strainer head including an inner member, a surrounding plate for supporting the same, and a thread and shoulder on the member and plate coacting to secure the member and plate together.

2. A machine of the character described comprising, a head, an inner member for the strainer head, a plate secured to the machine head and surrounding said member, and oppositely facing shoulders formed on said member, the one for abutting engagement with the machine head and the other for abutting engagement with the plate.

3. A machine of the character described comprising, a head, an inner member for the strainer head, a plate secured to the machine head and surrounding said member, oppositely facing shoulders formed on said member, the one for abutting engagement with the machine head and the other for abutting engagement with the plate, and a screw threaded engagement between the said member and plate.

4. A strainer head including an inner mem-

ber, said member being provided with longitudinally disposed rows of perforations, and passages intermediate said rows for the circulation of a temperature controlling medium 5 therein.

5. A strainer head including an inner member, said member being provided with longitudinally disposed rows of perforations and having formed therein a plurality of U-shape 10 passages for the circulation of a temperature controlling medium therein, each of said U-shape passages surrounding a row of perforations.

6. A strainer head including an inner member 15 having its wall composed of longitudinally disposed portions, said portions being alternately perforate and imperforate, and passages formed in said imperforate portions for the inflow and outflow of a temperature 20 controlling medium.

7. A strainer head including an inner member, said member having an enlarged rear portion, and means for circulating a temperature controlling medium in the member, said 25 means including longitudinally disposed passages formed in the member and annular passages formed in its enlarged rear portion.

8. A strainer head including a jacket composed of a plurality of parts, and a ring nut 30 adapted to engage the said parts when in operative position for locking them in said position, said nut and parts being provided with complementary interrupted threaded portions for constituting a breech-block lock.

35 9. A strainer head including a jacket composed of a plurality of parts, and a ring nut adapted to engage the said parts when in operative position for locking them in said position, said nut and parts being provided 40 with complementary interrupted conical threaded portions for constituting a conical breech-block lock.

10. A strainer head including cylindrical inner and outer members arranged in spaced 45 relation for establishing a chamber therebetween, and diametrically opposed partitions removably secured between said members for supporting said outer member and dividing the chamber into a plurality of longitudinal 50 semi-cylindrical parts.

In testimony, that I claim the foregoing as my invention, I have signed my name this third day of August 1927.

VERNON ROYLE.
